UNITED STATES PATENT OFFICE.

JAMES H. PAIGE, OF MANCHESTER, NEW HAMPSHIRE.

COMBINED NAME-PLATE AND REGISTER FOR DOORS.

No. 854,598.

Specification of Letters Patent.

Patented May 21, 1907.

Application filed July 6, 1905. Renewed November 8, 1906. Serial No. 342,568.

To all whom it may concern:

Be it known that I, JAMES H. PAIGE, a citizen of the United States, residing at Manchester, in the county of Hillsboro and State of New Hampshire, have invented certain new and useful Improvements in a Combined Name-Plate and Register for Doors; and I do hereby declare the following to be a full, clear, and exact description of the invention, such as will enable others skilled in the art to which it appertains to make and use the same.

My invention is for improvements in combined name plates and registers for doors.

As indicated, objects of my invention are to provide a name-plate which shall be adapted to convey certain information to those without, calling in the absence of the occupant or at other times, and to these ends the invention consists of certain structural features substantially as hereinafter fully disclosed and particularly pointed out by the claims.

In the hereto annexed drawing Figure 1 is a front view and Fig. 2 is a sectional elevation of the preferred embodiment of my invention. Fig. 3 is a disassembled view of the face-plate. Fig. 4 is a like view of the "backing" for said plate, and Fig. 5 is a detailed perspective view of the knob removed.

In the disclosure of my invention, I produce, preferably, in circular-form the face-plate 1 and the "backing", or disk 2, conformably thereto; and back of all is arranged a correspondingly shaped piece or second disk 3, preferably of wood, or which may be of that material or otherwise. Said face-plate bears the name of the owner, preferably stamped, or cut in stencil-form therein; the same being arranged in conformity with an arc of and adjacent to the circle or perimeter thereof. A portion of said face-plate is also cut-away, as at 4, directly below said name and also coinciding with an arc of, and adjacent to said circle or perimeter, thus providing an arcuate viewing opening 4 at that point, the purpose of which will be apparent later. The "backing" or disk 2 is treated to a coating of black-paint, or enamel, thus combining with the stencil-formed letters to distinctly or clearly disclose the name, while said "backing" or disk has produced, upon it, so as to be viewed through said opening, certain information, as at 5, 5^a of importance to the owner as will be readily understood.

Said face-plate 1 has the movable "backing", or disk, 2, guided behind it in an annular up-raised portion 1^a thereof to permit the ready manipulation or turning of said "backing", or disk 2 therein, between it and the back 3 by a finger-piece or knob 6 suitably let into a conforming opening or socket 7 of said disk 2 and extending outward through an opening 8 in the face-plate as shown. Said knob is formed with a rounded portion 6^a, adapted to extend through the opening 8, in the face plate, and a small flattened projection 6^b, adapted to extend into the socket 7, while the inner face of the portion 6^a, where it projects laterally beyond the part 6^b, rests upon the face of the plate 2, preventing said knob from becoming clamped upon the face plate. The turning of the "backing" or disk 2, is, it will be readily understood, to permit the shifting thereof according to the information or notice it may be desired to display through the viewing opening 4 as will be noted from Fig. 1.

In order to limit the rotation of the disk 2, I provide it with an arcuate slot 9 through which extends a screw 10 from the face-plate into the backing 3. By tightening said screw, the disk 2 may be held stationary while when it is loosened, said disk may be freely rotated.

I claim—

1. A device of the character described, having a face plate, an axially movable plate arranged behind said face plate and visible through an opening in said face plate, and means for turning the rear plate, comprising a knob having a rounded portion adapted to extend through an opening in the face plate, and a smaller plate-like portion adapted to engage a correspondingly shaped opening in said rear plate, the part of the rounded portion, which extends laterally from the plate portion, adapted to engage the surface of the rear disk for the purpose specified.

2. A device of the character described, comprising a face plate having a name formed therein by stencil-cut letters, and an axially movable plate, of a different color from the face plate, arranged behind said face plate and showing through said stencil-cut letters, said rear plate bearing indicia discernible through an opening in another portion of said face plate, means for turning the rear plate, comprising a knob having a rounded portion adapted to extend through an open-

ing in the face plate, and a smaller flattened portion adapted to engage a correspondingly shaped opening in said rear plate, the part of the rounded portion, which extends laterally from the flat portion, adapted to engage the surface of the rear disk for the purpose specified.

In testimony whereof, I affix my signature, in presence of two witnesses.

JAMES H. PAIGE.
